UNITED STATES PATENT OFFICE.

LOUIS J. JOHNSON, OF MISHAWAKA, INDIANA, ASSIGNOR TO JOHNSON BROS. ENGINEERING CORPORATION, OF SOUTH BEND, INDIANA.

OUTBOARD MOTOR FOR SMALL CRAFT.

Application filed January 5, 1924. Serial No. 684,563.

To all whom it may concern:

Be it known that I, LOUIS J. JOHNSON, a citizen of the United States, residing at Mishawaka, in the county of St. Joseph and State of Indiana, have invented certain new and useful Improvements in Outboard Motors for Small Craft, of which the following is a specification.

The invention relates to outboard motors for small craft, and has for its object to provide in combination with a pivotally mounted motor having a depending tubular casing, which casing is rotatably mounted in a supporting sleeve at its upper end, and provided with a sleeve intermediate its ends having interlocking means cooperating with a stationary member, means whereby water from a pump adjacent the lower end of the tubular casing will be conducted through a pipe, which pipe extends through sleeves between their inner and outer peripheries where the pipe will not interfere with the rotation of the motor and tubular casing.

A further object is to provide a discharge pipe from the water jacket of the motor, which pipe extends downwardly through the upper supporting sleeve of the tubular casing.

A further object is to provide in combination with a pivotally mounted and vertically movable outboard motor, said motor being supported on a sleeve adjacent its upper end carried by the drive shaft casing, and provided with a sleeve intermediate its ends rotatably mounted between slotted arms having a member cooperating with interlocking means carried by the sleeve, a water supply pipe for the water jacket of the motor, which supply pipe is disposed outside of the tubular drive shaft sleeve, thereby allowing a maximum diameter of drive shaft and to extend the water supply pipe through the sleeves carried by the tubular drive shaft sleeve, in a manner whereby they will not interfere with the rotation of the motor and tubular drive shaft sleeve carried thereby.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a side elevation of an outboard motor, showing the water supply pipe and discharge pipe applied thereto.

Figure 2 is a vertical longitudinal sectional view through the motor and drive shaft tubular casing and the supporting means for the motor.

Figure 3 is a horizontal sectional view taken on line 3—3 of Figure 2.

Figure 4 is a modified form of upper sleeve showing a horizontal section therethrough.

Figure 5 is a horizontal sectional view taken on line 5—5 of Figure 1.

Referring to the drawing, the numeral 1 designates the water jacket of the motor, 2 a water supply pipe connected to said jacket and 3 a water discharge pipe connected to said jacket, through which pipes water passes to and from the water jacket of the motor for cooling purposes. The casing 1 is supported on a vertically disposed rotatable sleeve 4, which sleeve is brazed or otherwise secured to the upper end 5 of the tubular drive shaft casing 6, consequently rotates with the casing 6 during the directional steering of the boat by the rotation in a horizontal plane of the motor. Sleeve 4 is rotatably mounted in a split sleeve 7, which last named sleeve is pivotally connected at 8 to a bracket 9, which is secured to a boat 10, therefore it will be seen that the motor as a whole is pivotally movable

in a horizontal plane, as well as pivotally movable in a vertical longitudinal plane for steering purposes, or for raising the propeller 11 when going through shoal water. Secured on the tubular drive shaft casing 6 intermediate its ends, is a second sleeve 12, which second sleeve rotates with the tubular casing 6 and is provided with segmentally shaped flanges 14, which flanges upon a rotation of the motor, when the casing 6 is in a vertical position, overlie the flanges 15 of a segmentally shaped plate 16, which is adjustably mounted between slotted segmentally shaped arms 17, which prevent the motor from pivotal movement in a vertical plane upon reversal of the motor as a whole, for instance when backing.

It will be seen that if the water supply pipe 18, which leads from the pump 19, adjacent the lower end of the casing 6, is disposed outside of the sleeve 12 and the

sleeve 4, it will interfere with the rotation of the motor by engagement with the supporting means for the sleeve 7, and the segmentally shaped plates or guide arms 17. On the other hand if the pipe is disposed within the tubular casing 6, said casing would necessarily have to be of considerable diameter or the drive shaft disposed therein relatively small diameter. To obviate the above difficulties the pipe 18 extends through the sleeves 12 and 4 intermediate their inner and outer peripheries, preferably through vertically disposed apertures 20 where the pipe will not interfere with the rotation of the motor by the supporting members for the sleeves 4 and 12. Although apertures 20 have been described, it is obvious that vertically disposed channels 20a may be used as shown in Figure 4, if desired, however in either case the pipe 18 is disposed between the inner and outer peripheries of the sleeves 4 and 12. Supply pipe 2 is connected at 21 to the upper end of the sleeve 4 where it will receive its supply of water from the pipe 18.

The discharge pipe 3, which leads from the water jacket of the engine is connected at 22 to the upper end of the sleeve 4 and discharges into a pipe 23, which extends through an aperture 24 in the rear side of the sleeve 4, said pipe 23 preferably extends downwardly from the lower end of the sleeve 4 where its discharge end 25 will be disposed below the water level, but in a position where it will not interfere with the rotation of the motor and its casing 6.

From the above it will be seen that a water supply and discharge pipe is provided for water jackets of out-board motors, which motors are pivotally mounted in supporting sleeves, and the pipes disposed in a position where they will not interfere with the free rotation of the motor in its supporting bearing. It will also be seen that the pipes will not only allow free rotation of the motor, but at the same time will also allow the tubular casing 6 to be of a minimum diameter and a maximum diameter of drive shaft to be used within the casing 6.

The invention having been set forth what is claimed as new and useful is:—

1. The combination with an outboard motor having a tubular drive shaft casing, a locking sleeve carried by the outer side of said drive shaft casing, said sleeve being rotatably mounted in a segmentally shaped plate, a water jacket carried by the motor, a pump rotatable with the shaft casing and disposed beneath the sleeve, of a pipe con-

nexion between the water jacket and the pump, said pipe connection extending through the sleeve between the inner and outer peripheries thereof.

2. The combination with an outboard motor, a tubular drive shaft casing carried by said motor, a sleeve carried by the drive shaft casing and located outside thereof said sleeve being rotatably mounted in a supporting bracket, a water jacket carried by the motor, a pump disposed below the sleeve, of a pipe connected to the pump and the water jacket, said pipe extending through the sleeve, a second pipe connected to the water jacket, said last named pipe extending downwardly through the sleeve and discharging below the sleeve.

3. The combination with an outboard motor, a drive shaft casing carried by said motor, a sleeve adjacent the upper end of said casing, said sleeve being rotatably mounted in a supporting bracket, a second sleeve intermediate the ends of the casing and rotatable therewith, fixed interlocking means for said last named second sleeve, a pump carried by said casing, a water jacket carried by the motor, of a pipe connection between the pump and the water jacket, said pipe connection extending through the sleeves carried by the casing.

4. The combination with an outboard motor, a drive shaft casing carried by said motor, a sleeve adjacent the upper end of the casing, said sleeve being rotatably mounted in a supporting bracket, a second sleeve intermediate the ends of the casing and rotatable therewith, fixed interlocking means for said last named sleeve, a pump carried by said casing, a water jacket carried by the motor, of a pipe connection between the pump and the water jacket, said pipe connection extending through the sleeves carried by the casing, a discharge pipe connected to the water jacket, said discharge pipe extending downwardly through the upper sleeve.

5. The combination with an outboard motor, a drive shaft casing carried by said motor, a sleeve carried by said casing and rotatable therewith, a second sleeve in which said first mentioned sleeve is rotatably mounted, a motor carried by said casing and having a water jacket, a water intake pipe carried by said motor, a water discharge pipe carried by said motor, said pipes extending through said first mentioned sleeve outside the casing.

In testimony whereof I affix my signature.

LOUIS J. JOHNSON.
